HOLDER FOR DENTAL FLOSS

Reese L. Anderson, 2712 SE. 58th Ave.,
Portland, Oreg. 97206

Filed Jan. 26, 1973, Ser. No. 326,605

Term of patent 14 years

Int. Cl. D24—04

U.S. Cl. D24—1 D

Fig. 6.

Fig. 1.

Fig. 2.

Fig. 4.

Fig. 5.

FIG. 1 is a left side elevation of a dental floss holder showing my new design;

FIG. 2 is a top plan view of the holder;

FIG. 3 is a right side elevation of the holder;

FIG. 4 is a bottom plan view of the holder;

FIG. 5 is a view of one end of the holder; and

FIG. 6 is a view of the opposite end of the holder.

I claim:

The ornamental design for a holder for dental floss, as shown.
